(57) CLAIM

I claim the ornamental design for a table, as shown and described.

DESCRIPTION

FIG. 1 is a front perspective view of my table;

FIG. 2 is a front view thereof;

FIG. 3 is a right side view, the left side (not shown) is a mirror image thereof;

FIG. 4 is a top view thereof;

FIG. 5 is an enlarged detailed view of the area designated as "FIG. 5" in FIG. 1; and,

FIG. 6 is a cross-sectional view cut along line 6-6 of FIG. 5 of my table.

1 Claim, 6 Drawing Sheets

FIG. 5
